Patent Office
Attest,

John G. Tolson, of Wrentham, Mass.
Letters Patent No 9945-Dated May 17th 1864.
Design for the Arm of a Sewing Machine.

DES. 1945

The schedule referred to in these Letters Patent and making part of the same.

To all whom it may concern:

It is known that I, John G. Tolson, of Wrentham, in the County of Worcester and State of Massachusetts,

have invented a new Design for the Pillar and Arm of a Sewing Machine; and I do hereby declare that the following is a full, clear, and exact description of the same, reference being had to the accompanying drawings forming a part of this specification, in which-

Fig. 1, is a front view of the pillar and arm.

Fig. 2, is a right hand side view of the same.

Fig. 3, is a section of the arm in the plane indicated by the line x, x in fig. 1.

Similar letters of reference indicate like parts.

The base of the pillar is composed of a lower circular member a, of fillet form and a torus b, from which the shaft A, rises with a spring as shown at c. The shaft A, is fluted like that of a column of the Ionic or Corinthian Order. The capital consists of a bead d, with fillets e, f, below and above it, and its top is of conical form as shown at g, and surmounted by an ornament, g, h, i, j, of the form of a cup or chalice containing a ball, the bowl, i, of the cup being made in the form of leaves. On the right side of the pillar opposite the arm B, there is a boss k, l, which is shaped like a flower and ornamented in petaloid form and some distance below there is a boss m, n, similarly formed and ornamented which merges into the base.

DES. 1945

The arm B has its lower part straight and of nearly cylindrical form in its transverse section as shown in fig. 3 and the upper part is ornamented with scroll work, p.y. as shown in figs. 1 and 3.

What I claim as my design, and desire to secure by Letters Patent, is—

The design and configuration of the pillar and arm of a sewing machine herein described and represented in the accompanying drawings.
